UNITED STATES PATENT OFFICE.

JOHN L. LAUGHLIN, OF RACINE, WISCONSIN.

ADJUSTABLE HARROW.

SPECIFICATION forming part of Letters Patent No. 274,125, dated March 20, 1883.

Application filed August 1, 1882. (No model.)

To all whom it may concern:

Be it known that I, JOHN L. LAUGHLIN, a citizen of the United States, residing at Racine, in the county of Racine and State of Wisconsin, have invented certain new and useful Improvements in Adjustable Harrows, of which the following is a specification.

This invention relates to that class of harrows in which means are provided for adjusting the teeth so as to set them at any desired angle.

My improvement consists in the features of construction and combination hereinafter described, and illustrated in the accompanying drawings, in which—

Figure 1 is a top or ground view of the harrow; Fig. 2, an end view as it appears with the teeth in a vertical position; Fig. 3, an end view, showing position with teeth inclined; Fig. 4, an enlarged side, and Fig. 5 an end, view of the main or tooth bar, the upright rocking arms, and the parallel bars.

Similar letters refer to similar parts throughout the several views.

To the main or tooth bar A of the harrow is attached a pair of upright metal arms or links, B B, so constructed as to bring their centers opposite to admit of their being attached to the bar A with one bolt or rivet, E. The inner faces of the portion extending above the bar A are at right angles to it and the proper distance apart to receive the parallel bars C C, to which they are pivoted by means of bolts or rivets D D, in which manner the tooth-bars A are connected to the parallel cross-bars C C throughout. Attached to the parallel bars C C is a lever, G, arranged to lock, by means of a spring-pawl or other suitable device, to a quadrant, F, secured to the upper bar, C, which lever G, driving the parallel bars C C in opposite directions simultaneously, im-

parts a reciprocating oscillating motion to the tooth-bars A A, thereby enabling the teeth to be inclined to clear them of trash, or set and held at any angle.

Heretofore various means have been devised for adjusting the teeth, and the operating-levers for oscillating the tooth-bars have been connected to the harrow in a variety of ways; but it will be observed that I employ above 50 the tooth-bar two sets of bars which are pivotally connected together by links, and also at their lower ends pivoted to the tooth-bars; also, that the lever is pivoted to one bar of each upper set, and that the links of each pair have their upper opposing faces in planes at 55 right angles to the axis of the tooth-bar. Arranging the links thus in pairs not only gives strength to the harrow, but prevents disarrangement of any of the parts by reason of the 60 strain incurred. The tooth-bars, being below the upper sets of connected bars, have all necessary swing, and, in fact, the whole structure is greatly simplified.

I claim—

The combination, in an adjustable harrow, of the tooth-bars A, with the links B secured in pairs to the tooth-bars, on opposite sides thereof, and pivoted to the bars C of the two upper sets of bars which lie in different planes 70 and are located transversely to the tooth-bars, and the lever G, provided with a latching device and pivoted to one bar of each upper set, each pair of links which embraces one bar of each set having their opposing faces in planes 75 at right angles to the tooth-bars, substantially as described.

JOHN L. LAUGHLIN.
